UNITED STATES PATENT OFFICE

2,632,577

METAL TANK

James Sacco, Saugus, Mass.

Application October 11, 1948, Serial No. 53,817

8 Claims. (Cl. 220—5)

1

The present invention relates to containers. From a more specific aspect, the invention relates to fluid-storage-and-transporting containers, such as metal oil tanks that are commonly mounted upon trucks.

According to present-day methods of manufacture, tanks of the above-described character are constructed by curving a continuous sheet of metal into cylindrical form of oval cross-section, and then welding the ends of the sheet to correspondingly oval-shaped vertically disposed horizontally alined end walls, the major axes of which are disposed horizontally. In order to permit of access to the man-hole domes disposed at the top of the tank between longitudinally disposed upward projecting flashings, longitudinally disposed platform treads or walks are provided, on along each side of the tank, projecting horizontally outward substantially in or slightly below the plane of the major axes. The flashings and the platforms are secured to the cylindrical wall of the tank by welding operations that raise unsightly lumps at the exterior junctions between the cylindrical wall, on the one hand, and the flashings and the platforms, on the other. It then becomes necessary to eliminate these unsightly lumps by grinding and this grinding is tedious and expensive.

An object of the present invention is to provide a new and improved tank or other fluid storage container.

Other and further objects will be explained more fully hereinafter, and will be more particularly pointed out in the appended claims.

The invention will now be more fully explained in connection with the accompanying drawings, in which Fig. 1 is a perspective of an oil tank embodying the present invention, looking from the rear of the tank; Fig. 2 is a vertical longitudinal section taken upon the line 2—2 of Fig. 4, looking in the direction of the arrows; Fig. 3 is a perspective of the man-hole structure shown in the tank of Fig. 1; Fig. 4 is a perspective similar to Fig. 1, with parts broken away, showing the tank partly completed; Fig. 5 is a fragmentary perspective of a metal plate for assembly with the partly completed tank shown in Fig. 4 to provide a lower wall for the rear compartment of the tank; Figs. 6, 7 and 8 are perspectives of properly shaped metal sheets for similar assembly with the partly completed tank shown in Fig. 4 to provide rear and front lower depending flanges and an upper tank wall, respectively; Fig. 9 is a fragmentary elevation, upon a larger scale, of a modified drain for the tank; Fig. 10 is a vertical

2

section taken upon the line 10—10 of Fig. 9, looking in the direction of the arrows; Fig. 11 is a fragmentary elevation similar to Fig. 9 of a further modification; Fig. 12 is a vertical section taken upon the line 12—12 of Fig. 11, looking in the direction of the arrows; Fig. 13 is a vertical transverse section taken upon the line 13—13 of Fig. 1, looking in the direction of the arrows, but upon a larger scale; Fig. 14 is a perspective similar to Fig. 8 of a modification; Figs. 15 and 16 are similar perspective of parts for attachment to the rear and the front, respectively, of the part shown in Fig. 14; Fig. 17 is a similar perspective of a depending-flange modification for attachment to the part shown in Fig. 8; Fig. 18 is an elevation of a truck, with the tank of the present invention mounted thereon; Fig. 19 is a fragmentary elevation of the same, upon a larger scale, partly in longitudinal section; and Figures 20 and 21 are perspectives of details of parts of the housing at the rear of the tank.

Metal tanks of the type illustrated herein are of oval shape, with the major axis of the oval horizontally disposed. The front and the rear sheet-metal end walls 16 and 18 are therefore shown of this oval shape, with their bottoms and tops and their adjacently disposed regions each increasing in width from its top and its bottom toward the center. Additional intermediately disposed similarly shaped sheet-metal walls may also be provided if it is desired to divide the tank into separate compartments for containing different oil fuels. One such additional wall is shown at 17, thus dividing the tank into two compartments, a front compartment between the walls 16 and 17, and a rear compartment between the walls 17 and 18.

An upper sheet-metal side wall 1, curved to conform to the upper portion of the oval-shaped walls 16, 17 and 18, may be secured to these walls at one side thereof, as shown in Figs. 1 and 13, by welding to the upper portions of bent-over flange margins 19, 20 and 21, respectively, of the walls 16, 17 and 18. A similar upper sheet-metal side wall 5 may similarly be secured to these walls 16, 17 and 18 at the other side thereof, as shown in Figures 1, 4 and 13. The front edge 34 of the wall 1 is welded to the flange 19, its rear edge 33 to the flange 21, and an intermediately disposed portion of the wall 34 to the flange 20. The wall 5 is similarly secured. The lower portion of the wall 1 terminates in a horizontally disposed ledge 31, and the lower portion of the wall 5 in a similar ledge 50. As shown clearly in Fig. 13, the ledges 31 and 50 extend outwardly

in a common horizontal plane, just below the major axis of the oval-shaped walls 16, 17 and 18.

The upper portion of the wall 1 terminates in a vertically upstanding wall 29, and the upper portion of the wall 5 in a similar wall 30 parallel to the wall 29. The walls 29 and 30 are longitudinally disposed, one on each side of two man-holes 4, one for each compartment of the tank.

The upper walls 1 and 5 of the tank, therefore, form coverings for the major portion of the upper part of the tank. Their lower portions, as already explained, terminate just below the horizontal major axes of the ovals, and a longitudinally disposed gap is formed between their upper portions.

In order to cover the remaining portion of the upper part of the tank, this gap is filled by a man-hole structure comprising a sheet-metal top-wall plate 2 provided with the man-hole openings 4 and curved to conform to the upper portions of the oval-shaped walls 16, 17 and 18. This plate 2 is welded to the upper portions of the walls 16, 17 and 18. Along its longitudinal edges 35 and 36, as shown at 81 and 82, it is welded also to the upper walls 5 and 1, respectively, at their junctions with their respective upwardly extending vertical-wall terminations 30 and 29. The transversely disposed edges 88 and 89 of the curved plate 2 are also welded to adjacently disposed structures. A vertically upstanding cross plate 3 is welded to the transversely disposed edge 88 and the front edges of the upstanding vertically disposed walls 29 and 30. The man-holes 4 are constituted of metal cylinders welded at 83 in corresponding openings of the plate 2. They may be closed by means of suitable man-hole domes, not shown.

The lower covering of the tank is constituted of a suitably curved sheet-metal bottom wall 15 welded to the lower portions of the flanges 19, 20 and 21 of the walls 16, 17 and 18. The front margin of the lower wall 15, for example, is shown welded at 72 to the inner edge of the lower portion of the flange 19. The front edge of the lower wall 15 is similarly shown welded at 73 to the peripheral edge of the wall 16. The upper side edges of the wall 15 are interiorly welded at 79 and 80, respectively, to the upper walls 5 and 1, the former at its junction with its horizontally disposed ledge 50, and the latter at its junction with its horizontally disposed ledge 31. A further line of exterior weld 77 is provided between one of the upper side edges of the wall 15 and the underside of the ledge 50, at its junction with the lower side edge of the upper wall 5, and a further similar line of exterior weld 78 is provided between the other upper side edge of the wall 15 and the underside of the ledge 31, at its junction with the lower side edge of the upper wall 1.

Sills 26 and 27 for supporting the tank on a truck 87 are welded at 74 at the lower exterior surface of the wall 15. The tank may be secured to the truck by means of bolts 102 passing through bed supports 101 of the tank and cooperating with nuts 104 and washers 103.

The ledge 31 is provided with a terminal depending lip 32, and the ledge 50 with a similar lip 51. A lip 38 at the free end of a ledge 37 of a front depending flange or skirt 12 is welded at 85 to the front portion of the lip 32, with the ledge 37 in the same horizontal plane as the ledge 31. A similar alined lip at the free end of a ledge 40 of a rear depending flange or skirt 13 is similarly welded at 85 to the rear portion

of the lip 32, with the ledge 40 in the same horizontal plane as the ledge 31. A horizontal longitudinally disposed platform tread or walk 11 is then welded at 86 to the exterior of the wall 1 at its junction with the ledge 31 and to terminally upstanding alined lips 91 at the upper ends of the depending flanges 12 and 13, at their junctions with the respective ledges 37 and 40. The rear edge 43 of the front depending flange 12 is welded to the front edge 44 of the rear depending flange 13.

Another horizontally disposed platform tread or walk 11 is similarly provided along the other side of the tank. Two depending front and rear

flanges or skirts are also provided, identical in construction with the front and rear flanges or skirts 12 and 13, except that they are the mirror images thereof. The rear depending flange or skirt 52 only is illustrated, provided with the ledge 53 and the upper lip 14, welded at 84 to the lip 51. The said other tread 11 is shown welded at 86 to the exterior junction between the upper wall 5 and the ledge 50, and also to the lip 14.

If desired, the depending flanges 12 and 13 may be replaced by a single depending flange 68, having a ledge 69 and a lip 70 to correspond to the ledges 37 and 40 and the lip 38. The depending flanges 12 and 13 are provided with an inwardly extending lip 39, the depending flange 52 with a similar lip 55, and the depending flange 68 with a similar lip 71.

The front portions of the front depending flange 12 and its non-illustrated counterpart are curved forward, as shown at 41. The rear portions of the rear depending flanges 13 and 52 are similarly curved rearward, as shown at 42. A rear wall 6 is welded along curved edges 92 to the rear edges 33 of the walls 1 and 5. Bent-in flanges 93 of the rear wall 6 are welded at corresponding bent-in flanges 94 of the portion 42. The upper portion of the rear wall 6 is provided with an upwardly curved tongue 90, the forward edge of which is welded to the rear edge 89 of the plate 2, and to a metal plate 105, Fig. 19. A bumper 10 is welded along edges 96 to edges 97 of the rear wall 6. Edges 99 of the bumper 10 are welded to edges 98 of the rear wall 6 and to the curved portions 42. A housing is thus provided at the rear of the tank, the floor of which is constituted of a plate 28, shown supported at 100, to provide a bottom wall for the housing. The portions 42 constitute integral rearward extending end walls of the flanges 13 and 52 to constitute end walls of the housing. Access to the interior of the housing may be had by raising a door 7 about hinges 8 by means of a handle 9. When closed, the door 7 engages a flange 95 of the bumper 10.

The curved plate 15 is shown integrally provided with two troughs 22 and 24, the former of which extends inward from the rear end through the rear compartment, between the walls 17 and 18, into the front compartment, between the walls 16 and 17, and the latter of which extends similarly into the rear compartment. A plate 23 is welded to the inner face of the curved plate 15, as at 75 and 76, over the trough 22, so as to prevent the contents of the rear compartment from entering the trough 22. The trough 22, therefore, provides communication between the front compartment only and the outside atmosphere, and the trough 24 with the rear compartment only. If more than two compartments should be provided through the addition of further inter-

mediately disposed walls 17; similar plates 23 would be similarly welded over the portions of the corresponding troughs that would extend through each compartment except the compartment or compartments into which the inner end of the corresponding trough terminates.

Fluid may be dispensed from the respective compartments by making suitable hose connections to the troughs 22 and 24 through drain connections 25, shown as externally threaded nipples. The oil is delivered from the drain connections 25 through a manifold and valves (not shown).

According to the modification illustrated in Fig. 14, the upper curved wall 56 is identical with the upper curved wall 1, the upstanding vertical wall 60 corresponding to the upstanding vertical wall 29 and the rear edge 61 to the rear edge 33. The ledge 31, however, is replaced by a platform tread or wall 57 of twice its width, and it is made integral with the depending flange or skirt 58 and the lip 59, which takes the place of the two depending flanges 12 and 13 and the lip 39. The front edge 63 of the depending flange is welded to the rear edge 67 of a separate front curved wall 66, and its rear edge 62 is welded to the front edge 65 of a separate rear curved wall 64.

The curved walls 66 and 64 may be employed also with the depending flanges 12 and 13 and also with the modification of Fig. 17, according to which the depending flanges 12 and 13 are replaced by a single flange or skirt 68 having a front edge 63, a rear edge 62, and a platform tread or walk 69.

Further modifications will occur to persons skilled in the art, and all such are considered to fall within the spirit and scope of the invention, as defined in the appended claims.

What is claimed is:

1. A metal container having end walls and bottom, top and side walls welded along their ends to the end walls, the side walls being each integrally joined at its bottom to an outward projecting platform and at its top to an upward projecting flashing, the side walls being welded at their junctions with the platforms to the sides of the bottom wall along the inner faces of the side walls and the bottom wall and along the outer faces of the bottom wall and the under faces of the platforms, and the side walls being welded at their junctions with the flashings to the sides of the top walls along the upper faces of the top walls and the inner faces of the flashings.

2. A metal container having end walls and one or more intermediately disposed walls each increasing in width from its top and its bottom toward its center, bottom and top walls welded along their ends and intermediately to the bottoms and to the tops and adjacently disposed regions of the end walls and the intermediately disposed wall or walls, and side walls welded along their ends and intermediately to the end walls and the intermediately disposed wall or walls between the bottom and the top walls and each integrally joined at its bottom to an outward projecting platform and at its top to an upward projecting flashing, the side walls being welded at their junctions with the platforms to the sides of the bottom walls and at their junctions with the flashings to the sides of the top walls.

3. A metal container having oval-shaped end walls, with the larger axes of the ovals horizontally disposed, bottom and top walls welded along their ends respectively to the bottom halves and

to the tops and adjacently disposed regions of the end walls, and side walls welded along their ends to the end walls between the bottom and the top walls and each integrally joined at its bottom to an outward projecting platform, and at its top to an upward projecting flashing, the side walls being welded at their junctions with the platforms to the sides of the bottom walls and at their junctions with the flashings to the sides of the top walls.

4. A metal container having end walls, one or more intermediately disposed walls that provide compartments between adjacently disposed end walls and the intermediately disposed wall or walls, a bottom wall provided with a plurality of troughs extending inward from one of the end walls into the respective compartments, a top wall and side walls, the bottom, top and side walls being welded along their ends and intermediately to the end walls and the intermediately disposed wall or walls, the side walls being each integrally joined at its bottom to an outward projecting platform and at its top to an upward projecting flashing, the side walls being welded at their junctions with the platform to the sides of the bottom walls and at their junctions with the flashings to the sides of the top walls, and a plate or plates welded over the portions of the trough or troughs that extend through each compartment except the compartment or compartments into which the inner end of the corresponding trough terminates, the troughs providing communication between the respective compartments and the outside atmosphere.

5. A metal tank having end walls each increasing in width from its top and its bottom toward its center, bottom and top walls welded along their ends to the bottoms and to the tops and adjacently disposed regions of the end walls, and side walls welded along their ends to the end walls between the bottom and the top walls and each integrally joined at its bottom to an outward projecting platform and at its top to an upward projecting flashing, the side walls being welded at their junctions with the platforms to the sides of the bottom walls, and a further platform welded to each platform in the plane thereof and provided with a depending apron.

6. A metal tank having end walls and bottom and top walls welded along their ends to the bottoms and to the tops and adjacently disposed regions of the end walls, two side walls welded along their ends to the end walls between the bottom and the top walls and each integrally joined to an outward horizontally projecting ledge, the side walls being welded at their junctions with the ledges to the sides of the bottom wall along the inner faces of the side walls and the bottom wall and along the outer faces of the bottom wall and the under faces of the ledges, and horizontal longitudinally disposed platform treads welded to the respective side walls at their junctions with the ledges.

7. A metal tank having end walls each increasing in width from its top and its bottom toward its center, bottom and top walls welded along their ends to the bottoms and to the tops and adjacently disposed regions of the end walls, two side walls welded along their ends to the end walls between the bottom and the top walls and each integrally joined at its bottom to an outward horizontally projecting ledge, the side walls being welded at their junctions with the ledges to the sides of the bottom wall along the inner faces of the side walls and the bottom wall and along the outer faces of the bottom wall and the under faces of the ledges, and horizontal longitudinally disposed platform treads welded to the respective side walls at their junctions with the ledges.

ledges to the sides of the bottom wall along the inner faces of the side walls and the bottom wall and along the outer faces of the bottom wall and the under faces of the ledges, and horizontal longitudinally disposed platform treads welded to the respective side walls at their junctions with the ledges.

8. A metal tank having substantially oval-shaped end walls, with the larger axes of the ovals horizontally disposed, bottom and top walls welded along their ends to the bottom halves and to the tops and adjacently disposed regions of the end walls, two side walls welded along their ends to the end walls between the bottom and the top walls and each integrally joined at its bottom to an outward horizontally projecting ledge having a terminal depending lip, the ledges being disposed in a common horizontal plane just below the major axis of the oval-shaped end walls, the side walls being welded at their junctions with the ledges to the sides of the bottom wall, and two depending skirts each having a ledge with a depending lip at its

10

15

23

free end and a terminally upstanding lip at its upper end at its junction with its ledge, the skirt ledges being disposed in the said horizontal plane with their lips welded to the lips of the respective side-wall ledges, and horizontal longitudinally disposed platform treads welded to the respective side walls at their junctions with their ledges and to the upstanding lips.
